STOKER

Howard P. Anderson, deceased, late of Erie, Pa.,
by Bernadine Anderson, executrix, Dallas, Tex.,
assignor to The Standard Stoker Company,
Inc., New York, N. Y., a corporation of Dela-
ware

Original application March 28, 1933, Serial No.
663,131. Divided and this application April
17, 1937, Serial No. 137,471

3 Claims. (Cl. 110—104)

This invention relates to stokers and more particularly to stokers arranged to deliver fuel to a furnace through the lower portion of an opening in an upstanding wall thereof arranged to permit power and manual feeding of the fuel.

It is an object of the invention to provide an improved stoker arranged with a firedoor to occupy a minimum of space at the firing opening to permit the use of smaller firing openings than heretofore employed.

More specifically it is an object of the invention to provide a novel stoker conduit communicating with the lower portion of a furnace firing opening, the conduit having a novel hinged cover, and a particularly designed firedoor for the upper portion of the firing opening, the hinged cover and firedoor cooperating to arrest upward movement of the former by the fuel stream passing through the conduit and preventing accidental blowing out of the latter, as when an explosion occurs in the boiler firebox.

With the above and other objects in view, the invention resides in the construction of the individual elements and their relation one with another as will be apparent from the following description when read in connection with the accompanying drawings, wherein

Fig. 1 is a view in vertical longitudinal section of a portion of a locomotive with the stoker shown in operative position, parts of the stoker being in elevation and parts broken away;

Fig. 2 is a view in end elevation of the stoker looking toward the firebox;

Fig. 3 is a sectional view taken on the line 3—3 of Fig. 1; and

Fig. 4 is a sectional view taken on the line 4—4 of Fig. 1.

In the drawings, the locomotive is indicated generally by the numeral 10 and includes the backhead 11 of the firebox 15, constituting a rear water leg of the locomotive boiler. The backhead 11 has an opening 16 therethrough arranged to form both a hand firing opening and a stoker firing opening.

A firedoor frame 15 embraces the firing opening 16 in the boiler backhead 11, the lower portion of the frame being arranged to receive the stoker riser conduit 18. At its upper end, the riser conduit 18 is provided with a cover or hood 19 which is hinged to the rear wall 20 of the riser conduit on the transversely extending pins 21. The cover 19 is arcuate in transverse cross section and a flange or bead 22 is formed slightly rearward of the forward end of the cover and is in spaced relation with the firedoor frame 15.

Mounted on the frame 15 is a pneumatically operated firedoor 23 which consists of the pivotally mounted door sections 24, 25. The door sections 24, 25 fit snugly between the frame 15 and the flange 22 and have their lower portions cut away as at 26 to conform with the arcuate-shaped top wall 27 of the cover 19. By this arrangement, the bead 22 prevents the outward thrust of the firedoor 23 when an explosion occurs in the boiler firebox, while the lower portion of the firedoor engages the forward end of the cover 19 and arrests its upward movement by the fuel stream passing through the riser conduit. Thus, the firedoor 23 forms a closure for the upper portion of the firing opening 16 and when the fireman finds it necessary to inspect the condition of the fire or to supply fuel manually, the firedoor 23 may be opened by power or manually by the handle 28. The portion of the firing opening thus exposed is sufficient for such purposes. When it is necessary to gain access to the interior of the firebox for the purpose of making inspection or repairs of the grates, firebox sheets or flues, the firedoor 23 may be opened in the usual manner and the cover or hood 19 swung rearwardly, thereby uncovering the entire opening.

The riser conduit 18 is received by the frame 15 in a novel manner which permits said conduit to be conveniently located with respect to the firing opening. For this purpose, the frame 15 is provided with side flanges 29, 30 and the riser conduit has formed therewith the flanges 31, 32. In erecting the stoker, a rod 33 is passed through the flanges 29, 30, 31 and 32 and the riser may then be turned about this rod until the desired position of the riser has been established. Bolts such as 34 and 35 are then passed through the flanges 29 and 30 of the frame and are threaded into the side flanges 31 and 32 of the riser 18 whereby a rigid connection is obtained.

A pressure fluid distributor head 36 issues blasts of fluid across the distributor plate 37 for projecting fuel to all parts of the firebed. The distributor plate 37 is secured to the riser 18 by bolts such as 38 and is provided with side wings 39 and 40 formed integrally therewith for preventing coal from spilling over the side edges of the plate.

From the foregoing it will be realized that a novel stoker for feeding fuel through the firing opening has been constructed which is of a simple and durable nature and in which the parts are so organized that access to the firebox may

be made conveniently. The appended claims define the scope of the present invention.

This application is a division of Howard P. Anderson's co-pending application Serial No. 5 663,131, filed March 28, 1933, for improvements in Stokers, now Patent No. 2,081,113, granted May 18, 1937.

It is claimed:

1. In a locomotive provided with a firebox having a firing opening in the backwall thereof, a stoker comprising an upwardly and forwardly extending fuel feed casing communicating with the lower portion of said firing opening, said casing having a separable upper portion forming a cover over the upper end of the casing, said cover being concave in configuration and arcuate in transverse and longitudinal vertical cross section, said cover being hinged to the upper rearward end of said casing for rearward swinging movement about a horizontal transverse axis, and a firedoor for the upper portion of said firing opening, the lower edge of said firedoor having an arcuate centrally disposed indentation conforming with the shape of said cover and fitting closely thereagainst.
2. In a locomotive provided with a firebox having a firing opening in the backwall thereof, a stoker comprising an upwardly and forwardly extending fuel feed casing communicating with the lower portion of said firing opening, said casing having a separable upper portion forming a cover over the upper end of the casing, said cover being concave in configuration and arcuate in transverse and longitudinal vertical cross section, said cover being hinged to the upper rearward end of said casing for rearward swinging movement about a horizontal transverse axis, said cover having an arcuate transverse upstanding flange near its forward end, and a firedoor for the upper portion of said firing opening mounted on said frame and arranged to swing laterally and upwardly, the lower edge of said door being included between said flange and said frame and having an arcuate centrally disposed indentation to conform with that portion of the cover extending forwardly from said flange and fitting closely against the arcuate surface of the said portion of said cover, said door being arranged to swing laterally and upwardly.

ing flange near its forward end, and a firedoor for the upper portion of said firing opening, the lower edge of said door being included between said flange and said firing opening and having an arcuate centrally disposed indentation to conform with that portion of the cover extending forwardly from said flange and fitting closely against the arcuate surface of the said portion of said cover, said door being arranged to swing laterally and upwardly.

3. In a locomotive provided with a firebox having a firing opening in the backwall thereof, a frame embracing said firing opening, an upwardly and forwardly extending fuel feed casing communicating with the lower portion of said firing opening, said casing having a separable upper portion forming a cover over the upper end of the casing, said cover being concave in configuration and arcuate in transverse and longitudinal vertical cross section, said cover being hinged to the upper rearward end of said casing for rearward swinging movement about a horizontal transverse axis, said cover having an arcuate transverse upstanding flange near its forward end, and a firedoor for the upper portion of said firing opening mounted on said frame and arranged to swing laterally and upwardly, the lower edge of said door being included between said flange and said frame and having an arcuate centrally disposed indentation to conform with that portion of the cover extending forwardly from said flange and fitting closely against the arcuate surface of the said portion of said cover.

BERNADINE ANDERSON,
*Executrix of the Estate of Howard P. Anderson,
Deceased.*
